UNITED STATES PATENT OFFICE.

WILLIAM H. BACHTEL, OF CANTON, OHIO, ASSIGNOR OF ONE-FOURTH TO
HIRAM ZERBA, OF SAME PLACE.

RAILWAY SIGNALING APPARATUS.

SPECIFICATION forming part of Letters Patent No. 256,266, dated April 11, 1882.

Application filed December 2, 1881. (No model.)

To all whom it may concern:

Be it known that I, WILLIAM H. BACHTEL, a citizen of the United States, residing at Canton, in the county of Stark and State of Ohio, have invented certain new and useful Improvements in Railway Signaling Apparatus; and I do hereby declare that the following is a full, clear, and exact description of the same, reference being had to the annexed drawings, making a part of this specification, and to the letters and figures of reference marked thereon.

Figure 1 is a perspective view of my invention, showing the flags in an elevated position to indicate "danger," and Fig. 2 is a detail view, on an enlarged scale, showing the operating-levers in their normal position.

The present invention has relation to certain new and useful improvements in railway signaling apparatus; and it consists in the details of construction, substantially as shown in the drawings and hereinafter described.

In the accompanying drawings, A B designate two posts, let into the ground or otherwise supported in an upright position. To the upper end of the posts A B are connected two pulleys, *a b*, over which passes a wire or other suitable rope, *c*. This wire or rope *c* is endless, and is connected to the grooved pulleys *a b*, as shown in the drawings, each of said pulleys having connected thereto an operating cord, rope, or wire, *d*. These cords, ropes, or wires pass over small grooved pulleys *e*, connected to the upper ends of posts C, and extend down and around small pulleys *f*, connected to the lower ends of the posts C, near the ground. After the cords *d* pass around the pulleys *f* the ends thereof are connected to levers *g*, said levers being in turn pivoted to standards *h*.

Connected to the standards *h* are suitable springs, *i*, which operate to throw the levers *g* in a direction toward the posts to bring the hammers *k* in contact with the bells *l*, the same being connected to the posts C.

The wires or ropes *d* are attached in any convenient manner to the staffs of signal-flags D, the ends of said staffs being pivoted in any suitable manner to supports on the posts C, so

that the flags may be raised or lowered, as desired.

To the shafts of the pulleys *a b* are rigidly connected levers E F, extending down to near the ground, their ends bearing against springs G, secured to the posts A B. The springs G, which bear with great force against the levers E F, prevent the possibility of the levers being moved by any force except that exerted by the passing engine, thereby rendering it impossible for the levers to be moved by malicious persons.

The engine of the train, at its forward end and side, must have connected to it an extended arm, by which the signaling apparatus is operated, which acts in the following manner:

The normal position of the levers E F when the flags D are down being shown in full lines, Fig. 2, the train as it passes along over the track in a direction as indicated by the arrows, Fig. 1, the extended arm on the forward end and side of the engine, when brought in contact with the lever E of post B, will cause the levers E F of both posts A and B to assume the position as indicated in Fig. 1, the levers F occupying the position formerly occupied by the levers E. This movement of the levers on both the posts A B is caused by the pulleys *a b* and the connecting cord or wire *c*, which also, by pulling in the cords *d*, will raise the signal-flags D and bring the levers *g* in position as shown in Fig. 1 of the drawings.

By the position of the levers as shown in Fig. 1 it will be noticed that the lever E upon the post A is in position to be operated in like manner by the engine as it passes, thereby bringing the levers of both posts again in their normal position, as shown in Fig. 2, turning the pulleys *a b* in a reverse direction, lowering the signal-flags, and by the assistance of the springs *i* causing the lower end of the pivoted levers *g* to be elevated out of reach of the extended arm upon the engine of the next train.

The posts A B C, it should be understood, are arranged a considerable distance apart, and should a train of cars pass the post C before the engine of a forward train had operated the

levers of the post A, the lever *g* being in position as illustrated in Fig. 1, the arm upon the engine of said succeeding train would strike the lever *g* and cause an alarm to be sounded.

- 5 I do not desire to be understood as confining myself to any particular alarm-sounding device arranged to be operated by the levers *g*, as a gong may be substituted for the bell, and possibly would be better in case of heavy fogs.
- 10 It should be understood that the signal-flags remain raised only so long as the levers of the post A are not reached and operated by the passing engine, and at any time before this occurs the lever *g* is in position to be operated by a succeeding engine, and thus sound an alarm to notify the engineer that the preceding train has not reached the second signal-flag or passed around the curve, as the case may be. The alarm is only necessary in case of a heavy
- 15 fog or where the signal-flag is not seen by the engineer.

The signaling apparatus may be also employed for use in cross-roads to notify persons that a train is approaching, a flag in such case being connected to the cord or wire *c* between the pulleys *a b* in any suitable manner that will admit of the flag being raised or lowered similar to the signals D.

A spring or weight may be connected to the cords *c*, when of metal, to allow for contraction and expansion by the heat and cold, and it is preferable that a cap or suitable cover should

be placed over the several pulleys and bearings of the apparatus, also the bells, to protect them from the snow or storms.

The posts A B are firmly held in an upright position by braces H, of the form shown in the drawings, so that there will be no possibility of the posts being affected by heavy windstorms.

Having now fully described my invention, what I claim as new, and desire to secure by Letters Patent, is—

1. In a railway signaling apparatus, the flags D and cords or wires *d*, in combination with the levers E F and springs G, substantially as and for the purpose specified.

2. In a railway signaling apparatus, the signal-flags D, and cords or wires *d c*, in combination with pulleys *a b* and levers E F, constructed and arranged to operate substantially as and for the purpose described.

3. In a railway signaling apparatus, the combination, with the signal-flags D, wires or cords *d*, and levers E F, of the levers *g*, provided with a suitable alarm-sounding device, substantially as and for the purpose set forth.

In testimony that I claim the above I have hereunto subscribed my name in the presence of two witnesses.

WILLIAM H. BACHTEL.
